CLAIM

The ornamental design for a seat belt lap pillow and positioner for use by pregnant women, as shown and described.

DESCRIPTION

FIG. 1 is a front elevational view of a seat belt lap pillow and positioner for use by pregnant women; the broken lines are for illustrative purposes only, and form no part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
